CLAIM

(**) Term: **14 Years**

The ornamental design for connector design for warmed ear oximeter probe, as shown and described.

DESCRIPTION

FIG. 1 is a perspective view of a connector design for warmed ear oximeter probe showing our new design; FIG. 2 is a top plan view thereof;

FIG. 3 is a front elevational view thereof;

FIG. 4 is a right side elevational view, the left side elevational view being a mirror image thereof;

FIG. 5 is a rear elevational view thereof; and,

FIG. 6 is a bottom plan view thereof.

The broken lines showing the cord in FIGS. 1 and 5 are included for the purpose of illustrating environmental structure only and form no part of the claimed design.
